UNITED STATES PATENT OFFICE.

ANDREW SMITH, OF SAN MATEO, CALIFORNIA, ASSIGNOR TO SMITH METAL PERFORATING COMPANY, OF SAN MATEO, CALIFORNIA.

CORRUGATED SHEET-METAL SECTIONAL CASING FOR CULVERTS, DRAINAGE-CASINGS, &c.

1,049,543.

Specification of Letters Patent.

Patented Jan. 7, 1913.

Application filed April 13, 1912. Serial No. 690,519.

To all whom it may concern:

Be it known that I, ANDREW SMITH, a citizen of the United States, residing at San Mateo, in the county of San Mateo and State of California, have invented certain new and useful Improvements in Corrugated Sheet-Metal Sectional Casings for Culverts, Drainage-Casings, &c., of which the following is a specification.

10 My invention relates to sheet metal casings for culverts, drainage conduits, tunnels, etc., and more particularly to the "nestable" type, which are adapted to be transported in disconnected sections nested together and assembled at the place of use.

15 The main object of my present invention is to provide simple means for securing the complementary sections of the culvert or conduit together, and to form lateral flanged joints which constitute longitudinal strengthening ribs capable of resisting the pressures and lateral thrusts induced by the pressure of the load supported by the conduit and transmitted through the arches of the upper sections.

20 Another object is to reinforce the flange construction, and to give the assembled structure increased strength and rigidity.

25 With these and other objects in view which will appear from the following description, my invention consists in certain novel features of construction and combinations of parts disclosed in the accompanying drawings, in which—

30 Figures 1, 2, 3, and 7 are perspective views of corrugated casings for culverts and conduits showing my invention embodied in different forms or modifications; Fig. 4 is a detail cross-sectional view of my invention applied to a union joint connecting two adjacent casings; Figs. 5 and 6 are perspective views of arched culverts embodying my invention; Fig. 8 is a perspective view showing my invention applied to a sectional casing adapted to be used for cattle-passes, tunnels or shafts; Fig. 9 is a perspective view of a flume having reinforced flanges embodying my invention; Fig. 10 is a front elevation of an abutment or shield embodying my invention; and Fig. 11 is a vertical section showing the manner of connecting the abutment to the end of the conduit casing.

The complementary sections 1, 2, of the

sheet metal casing may be plain or corrugated, or partly plain and partly corrugated, as desired. I prefer the corrugated construction because of the far greater strength and rigidity. The lateral securing flanges or side seams, by which the upper and lower companion sections are united, receive the downward pressure due to the load supported by the upper arch, and the rivets or bolts passing through the flanges receive the shearing stresses tending to spread the arch of the upper section outwardly. It is the purpose of my invention to provide such a reinforcement to the flanges and the adjacent metal that the entire joint will be greatly stiffened and strengthened, and the lateral shearing stresses will be resisted by an anchorage upon the body of the adjacent metal.

25 The simplest form of my reinforced flanged joint is illustrated in Fig. 1. The metal of the flange is plain and uncorrugated, and after being turned outwardly, as at 4, the metal of the flange is returned or doubled upon itself and the end or projecting edge 5 of the sheet is then bent back 30 against the ends of the corrugations of the body portion, and bears laterally against the body of its own section, thereby forming an anchor or brace member for the flange and at the same time reinforcing the 35 metal adjacent the flange which is subjected to the crushing weight of the superimposed load upon the arch. The anchor or bracing member 5, therefore, performs a very important function in giving strength and 40 rigidity to the flange and the adjacent metal of the body portion. Aside from the two-fold strength of the two layers of metal in each section of the flange, any tendency of the flange to bend or yield transversely is 45 resisted by the auxiliary anchor or transverse bracing member 5, which transmits the lateral pressures upon the flange inwardly against the corrugated body portion. I prefer to corrugate the anchor-member 5 to 50 conform to the corrugations of the body portion, this being done simultaneously with the formation of the main corrugations.

55 In Fig. 2, the flange of the lower section is made wider than the flange of the upper section, and is turned upwardly to form a vertical retaining or lateral thrust member 6 which entirely relieves the rivets or bolts

9 of any shearing action due to the tendency of the upper arch to spread laterally. Note again that the lateral thrust upon the retaining-members or lips 8, is transmitted 5 through the anchor members 5 to the corrugated body portion, which adds very materially to the strength of the joint in addition to the doubling of the metal of the several parts of the union.

10 Instead of returning the auxiliary bracing member 5 upon the inside of the body portion, it may be bent back to abut the outside of the body member as shown at 5^a, in Fig. 3. In this form, I may employ an auxiliary 15 longitudinal strengthening and stiffening member in the shape of a T-iron 10, its web constituting a spacer between the upper and lower flange members, and being bolted thereto. The head or flange of the T-iron 20 bears against the inner sides of the adjacent sections and is preferably corrugated to conform to the walls of the sections. The head or flange of the T-iron forms an anchor to resist lateral thrust and any tendency of the 25 sections to spread. It will be understood that I may employ this auxiliary stiffening T-iron with the forms of flanges shown in any of the other figures. This form is also well adapted to the compound joint shown 30 in Fig. 4, uniting two adjacent parallel conduits or culverts. In this case the reinforcing bar is in the form of an I-beam 10^a, the opposite flanges of which bear against the adjacent inner walls of the respective cas- 35 ings.

The T-bar may be omitted as shown in Fig. 7. The transverse bracing member 5^a, as in the forms previously described, serves the two-fold function of resisting lateral 40 thrusts tending to bend the flange and of reinforcing the body portion at the terminals of the corrugations where pressures from the arch are received.

In Fig. 5, I have shown my reinforced 45 flange joint applied to an arched culvert or conduit. I prefer to corrugate both the upper arched section 1^a and the lower or flat bottom section 12. The reinforced lateral flange is substantially the same as that of Fig. 1, previously described. The returned member 4^a of the bottom is preferably carried back inside of the meeting line of the arched upper section in order to stiffen the pressure line of the base.

55 In Fig. 6, I have shown an arched culvert having a wide extended arched section 1^b, with the intermediate portion braced and supported by means of one or more I-beams 14, 14'. While I-beams of the ordinary form 60 may be employed, as shown at 14, I prefer to employ beams with corrugated flanges as shown at 14', which correspond with the corrugations of the culvert sections, in order to more effectually brace and support the walls 65 of the casing. When the beams are formed

of sheet metal, I prefer to also provide the web with transverse corrugations to strengthen and stiffen the beam. The reinforced flange joint is substantially the same as that previously described in connection 70 with Fig. 2. It is to be understood that I may employ the supporting I-beams in any of the casings illustrated in the several figures of the drawings.

My reinforced flange joint is adapted to 75 large casings intended for tunnels, or for the lining of mine shafts. In Fig. 8, I have shown a multi-sectional casing in the form of a cattle-pass adapted to pass through embankments. The outstanding reinforced 80 flanges 4, are formed substantially like those shown in Fig. 7, except that they are upon the inside of the casing instead of upon the outside. The sections of the casing may thus be assembled and these outstanding 85 flanges riveted or bolted from the inside, thereby adapting this form of casing to tunnels which are bored or driven through the earth. The end flange 4^b will be described in connection with Fig. 9. A plank or ce- 90 ment platform 18, may be placed across the bottom of the casing.

In Fig. 9, I have shown my reinforced flange applied to a flume comprising a single series of lower sections. In this case the 95 sides are extended into substantial parallelism to form a deeper channel. The lateral edges are provided with strengthening flanges 4^a, and the ends of the sections are united by flanged joints 4^b, each of which 100 embody my reinforced braced flange, sub- substantially in the form shown in Fig. 7, pre- viously described. It will be observed that the outstanding reinforced flange is braced against lateral bending strains by the aux- 105 iliary brace members 5^a which bear against the body portion. It is to be understood that the ends of adjacent sections of the cul- 110verts and conduits shown in all of the figures may be provided with reinforced braced flanges such as illustrated in Fig. 9. The brace member of the lateral flange is prefer- ably corrugated to fit the terminals of the body corrugations in the manner better shown in Fig. 7. A flume constructed in 115 this manner is exceedingly rigid, which is important when carried upon a trestle or other support in which the supports are spaced apart. The corrugations furnish rigidity transversely and the lateral rein- 120 forced flanges and brace members forming practically an angle iron construction, con- stitute stiffening and bracing members which make the flume very strong and rigid longi- 125 tudinally.

The terminals of the culverts or conduits which project from embankments are pro- vided with abutments or shields, and I prefer to employ my radially corrugated abut- 130 ment 20, illustrated in Fig. 10. The face of

the abutment or shield may be in a single plane or may be concave, so that any obstruction, as a falling tree, may not obstruct the opening or mouth of the culvert. It has 5 been proposed to corrugate the abutments either horizontally or vertically for the purpose of stiffening the metal, but in either case the abutment is strengthened only in one direction. The purpose of my radially 10 extending ribs or corrugations 21, is to produce a plate which shall resist the strains and pressures in all directions. The importance of this will be appreciated by engineers.

15 For the purpose of stiffening the margins of the abutment, I provide each edge with my outstanding reinforced braced flange as previously described, and I also fold or bend the edges of the metal around the culvert 20 opening back to form a reinforced flange for the bolts or rivets securing the same to the end of the terminal culvert section, as illustrated in Fig. 11 in cross-section.

I have described the constructions illustrated in the accompanying drawings in detail for the purpose of disclosing embodiments of my invention, but I am aware that changes may be made therein without departing from the scope of my claims or from 30 the spirit of my invention.

I claim:—

1. A sheet metal culvert or conduit section provided with outstanding flanged edges having the metal doubled back upon 35 itself to form a reinforcement, and a brace member integral with said reinforcement and bearing laterally against the body portion of its section.

2. A corrugated sheet metal culvert, 40 flume, or conduit section, provided with outstanding flanged edges having the metal doubled back upon itself to form a reinforcement, and a corrugated brace member integral with said reinforcement and abutting 45 the body portion of the section, the corrugations of said member being in juxtaposition with the corrugations of the body portion.

3. A sheet metal culvert comprising a 50 series of sectional units and a terminal abutment connected into a continuous casing, said units consisting of complementary sections, said sections and terminal abutment being provided with corrugations and connected to each other by means of reinforced flanges, and each of said flanges having an 55 integral brace member and bearing laterally against the adjacent section.

4. A sheet metal casing for culverts, con-

duits, or tunnels, comprising complementary 60 sections, each provided with projecting flanged edges having the metal thereof returned upon itself, and a brace-member integral with the flanged edges and bearing laterally against the body portion of its 65 section.

5. A sheet metal casing for culverts, conduits, or tunnels, comprising complementary sections, each provided with projecting flanged edges having the metal thereof returned upon itself, a brace-member integral 70 with the flanged edges and bearing against the body portion of the section adjacent said edges, and a shaped iron member having a web extending between the meeting flanged 75 edges of adjacent sections and having a flanged head extending in opposite directions from the web and adapted to engage the edges of both sections.

6. A sheet metal casing for culverts, 80 conduits, or tunnels, comprising complementary sections, each provided with projecting flanged edges having the metal thereof returned upon itself, and a brace-member integral with the flanged edges and bearing 85 against the body portion of the section adjacent said edges, the flange upon one of said sections extending beyond the flange upon the complementary section and having an upturned lip to engage the outer edge of 90 said complementary flange.

7. A sheet metal casing for culverts, conduits, or tunnels, comprising complementary sections, each provided with projecting flanged edges having the metal thereof returned upon itself, and one of said sections 95 having a brace-member integral with the flanged edges and bearing laterally against the body portion of its section adjacent the flanged edge.

8. A sheet metal casing for culverts, conduits, or tunnels, comprising complementary sections, each provided with projecting flanged edges having the metal thereof returned upon itself, and one of said sections 105 having a brace-member integral with the flanged edges and bearing against the body portion of the section adjacent the flanged edge, the upper section having an arched wall, and an intermediate support extending 110 between the walls of the upper and lower sections.

In testimony whereof I affix my signature in presence of two witnesses.

ANDREW SMITH.
